(57) **CLAIM**

The ornamental design for a light fixture, as shown and described.

DESCRIPTION

FIG. 1 is a front side view of a light fixture showing our new design;

FIG. 2 is a rear plan view thereof, showing the top and bottom sides;

FIG. 3 is a left side view thereof;

FIG. 4 is a right side view thereof;

FIG. 5 is a top plan view thereof, showing the top and front sides;

FIG. 6 is a bottom plan view thereof; and,

FIG. 7 is a perspective view thereof, showing the front and right sides.

The broken lines depict portions of the light fixture and form no part of the claimed design.

The hatching in FIGS. 1, 5, and 7 indicates a contrast in appearance.
